UNITED STATES PATENT OFFICE.

PHILIP E. BLUM, OF DANSVILLE, NEW YORK.

DESIGN FOR A SHOE.

51,009.

Specification for Design.

Patented July 10, 1917.

Application filed August 3, 1916. Serial No. 113,026. Term of patent 7 years.

To all whom it may concern:

Be it known that I, PHILIP E. BLUM, a citizen of the United States, residing at Dansville, in the county of Livingston, State of New York, have invented a new, original, and ornamental Design for Shoes, of which the following is a specification, reference being had to the accompanying drawing, forming part thereof.

Figure 1 is a perspective view of a shoe made according to my design; and

Fig. 2 is a top plan view.

I claim:—

The ornamental design for a shoe as shown.

PHILIP E. BLUM.
